US00D416721S

United States Patent [19]

Schacht et al.

[11] Patent Number: Des. 416,721

[45] Date of Patent: ** Nov. 23, 1999

[54] SHELF UNIT

[75] Inventors: **William Frederick Schacht; Lynda Elizabeth Chesser**, both of East Grand Rapids, Mich.

[73] Assignee: **Herman Miller, Inc.**, Zeeland, Mich.

[**] Term: 14 Years

[21] Appl. No.: 29/088,619

[22] Filed: May 28, 1998

[51] LOC (6) Cl. 26-04

[52] U.S. Cl. D6/511

[58] Field of Search D6/477, 479, 509, D6/511, 566, 567, 574; 211/86, 88.01, 90.01, 90.04, 119.003, 126.1, 126.16, 134, 135, 153, 186-188; 108/59, 60, 47.11-47.17
